RECORD CHANGER APPARATUS

Farlow B. Burt, South Bend, Ind., assignor to
 Bendix Aviation Corporation, South Bend,
 Ind., a corporation of Delaware

Application July 16, 1948, Serial No. 39,030

7 Claims. (Cl. 274—1)

1

This invention relates to automatic phonographs and more particularly to trip mechanisms therefor.

In the mechanism of the present invention the power or actuating force required for operating the trip mechanism is taken directly from the main drive shaft to which other moving parts of the phonograph are connected. This has a distinct advantage over phonographs or record changers which rely on the tone arm to impart the actuating force to the trip mechanism. In the latter type construction there is the likelihood of forcing the needle of the pickup out of the grooves of a record if the actuating force required to operate the trip mechanism is too great.

It is a principal object of the invention to provide a simple, rugged, automatic phonograph which requires a minimum of attention during the playing of a stack of records.

Another object of the invention resides in the provision of a trip mechanism operable when the stylus, which is carried by the pickup arm, moves out of a playing groove into a non-playing groove to thereby initiate a record changing cycle.

A further object of the invention resides in the provision of a trip mechanism which receives its actuating force from a power source connected directly thereto.

A very important object of the invention resides in the provision of a trip mechanism which may be manually operated to start cycling of the machine before a record has been completely played.

A yet further object of the invention resides in the provision of a velocity controlled trip mechanism which is rendered operative upon movement of the pickup into the tripping grooves of a record.

A further object of the invention is to provide a phonograph apparatus having cycling means controlled by a velocity responsive trip mechanism.

The above and other objects and features of the invention will be apparent from the following description of the apparatus taken in connection with the accompanying drawing which forms a part of this specification, and in which:

Figure 1 is a vertical section taken on the lines 1—1 of the automatic phonograph of Figure 2 incorporating the invention, with parts omitted for clarity;

Figure 2 is a horizontal section taken on the lines 2—2 of the automatic phonograph of Figure 1, with parts omitted for clarity;

Figure 3 is a view taken on the lines 3—3 of 55

2

Figure 1 showing the trip mechanism of the invention with parts of the phonograph omitted for clarity, and with parts in phantom outline to more clearly show the relationship of the parts of the mechanism;

Figure 4 is a sectional view taken on the lines 4—4 of Figure 2; and

Figure 5 is a view of two of the levers of the trip mechanism.

Referring now to Figures 1 and 2 the reference numeral 10 designates a platform of a phonograph mechanism which may be supported in any suitable manner on vibration damping mountings, such as springs, not shown. The cycling mechanism of the phonograph apparatus includes an electric motor 12 that is carried by a bracket 14 bolted to the underside of the platform 10, by a bolt 16, which threadedly engages the platform. A gear box 18 is formed with an integral tubular extension 20 having a flange 22 at its outer end for securing the gear box to the motor, in any suitable manner. The motor 12 is provided with a shaft 24 having an end extending through the tubular extension 20 into the gear box 18. A 25 vertically extending shaft 26 has one end terminating in the gear box 18, where the shaft is drivably connected through gearing, not shown, to the motor shaft 24. A pinion gear 28 is fixed to the other end of shaft 26. The pinion gear 28, which rotates continually when the phonograph apparatus is being played, is provided with interrupted gear teeth 30 and continuous gear teeth 32 for a purpose hereinafter disclosed.

A record supporting mechanism or turntable 34 is swingably mounted on the upper end of shaft 36, to the lower end of which a gear 38 is fixed for driving engagement with a gear sector 40. A lever 42 connects the gear sector 40 to a circular cam element 44 provided with interrupted gear teeth 46 on its periphery for engagement with the pinion gear 28.

For releasably supporting a stack of records above the turntable three properly spaced shafts 48 are provided. The shafts extend vertically 45 above and below the platform 10. The upper ends of the shafts 48 are equipped with record slicing and supporting devices, not shown. The lower ends of the shafts carry sprockets 50, fixedly secured to the shafts, in any suitable manner. A continuous chain 52 passes over the three sprockets so that the shafts and consequently the slicers are driven simultaneously upon rotation of said cam wheel 44, which is drivably connected to one of said sprockets through a link 54.

A tone arm 56, having a pickup 58 articulated

thereto, is mounted on a vertical shaft 60 supported laterally in a double hub 62 integral with the platform 10 and extending above and below. The pickup or reproducer 58 is carried in gimbals 64 of the tone arm and is of a common form except that it is equipped with a double pointed needle 66 arranged to engage in the grooves in either the top or the bottom side of a record which is supported on the turntable. The lower end of the vertical shaft 60 is rounded at 68 so as to offer a minimum of friction to its sliding contact with an arm 70, of a bell crank 72, which raises and lowers the tone arm to the desired position above or below a record, as the case may be. The bell crank is supported on the underside of the platform and has its fulcrum at 74. An arm 76 of the bell crank is disposed at right angles to the arm 70 and is provided with a roller 78 arranged for rolling contact with an inner cam track 80 and an outer cam track 82 formed in the cam wheel 44. When the roller 78 rides in the inner cam track the tone arm is positioned for playing the top side of a record. With the roller in the outer cam track 82, the tone arm will come to rest vertically in a position for playing the bottom side of a record.

That part of the double hub 62 which depends below the platform 10, has a reduced diameter 84, which forms a bearing for a friction drive wheel 86, held in position by a snap ring 88. The periphery of the wheel 86 is constructed of a highly frictional material to insure traction between the wheel and a flange 90 integral with one end of a reciprocating lever 92, the other end of which is slotted at 94 to embrace a reduced section 96 of a hub 98. Said other end of the lever 92 is equipped with a cam follower 100 which fits into a groove 101 formed in the top side of the cam 44. The end of the reciprocating lever with which the flange 90 is integral is also slotted at 102 to embrace the reduced diameter 84 of the hub 62. The slotted end 102 is held in position by washers 103 encircling the reduced portion 84 of the hub 62, and located one on each side of the lever 92. A spacer is interposed between the lower washer and the top side of wheel 86. The width of slot 102 is greater than the reduced diameter 84 to permit relative lateral movement between the hub 62 and the end of the reciprocating lever 92 circumscribing said hub. One end of slot 102 is formed with a cam 99 which rides on the reduced diameter 84 of the hub, when the reciprocating lever is moved to the position shown in Figure 2 to thereby cause the flange 90 to move away from the periphery of wheel 86 so as to arrest the driving action imparted to the wheel through reciprocation of the lever. A spring 104 tends to rotate the lever 92 so that the flange 90 is in frictional engagement with the periphery of wheel 86.

The wheel 86 is equipped with a pair of diametrically opposed driving pins 105 which depend from the wheel for engagement with a cross bar 106 carried by the shaft 60, see Figure 3. The cross bar is formed with diametrically positioned slots 107 and 108 for sliding engagement with the driving pins 105. This arrangement between the driving wheel 86, which rotates the tone arm laterally, and the vertical shaft 60, which positions the tone arm vertically, provides for concurrent raising or lowering action of the tone arm in conjunction with lateral or swinging movement thereof.

The invention herein resides in the provision of a trip mechanism for sensing the end of a playing

groove of a record to thereby initiate cycling of the automatic phonograph. To this end there is provided a velocity sensitive mechanism including a lever 110 arranged to swing periodically about the pivot 111. This periodic movement is imparted to the lever by having one end thereof biased by a spring 112 into contact relationship with a revolvable cam 113, suitably secured to the drive shaft 26. To the other end of the lever 110 is pivotally mounted an actuating pin 114 for pushing engagement with one end of a lever 115 which is pivotally carried at 116 on the underside of the platform 10. Overlying said other end of the lever 110 and pivotally carried at 111, is a lever 117 arranged for limited relative angular movement with respect to lever 110. This limited movement, or lost motion between levers 110 and 117 is accomplished by the use of a pin 118 which is mounted on lever 110 and projects into an oversized opening 119 of the lever 117. For positioning the actuating pin 114 for pushing engagement with the lever 115 a pin positioning member 120 is rotatably mounted at one end of the lever 117. As best shown in Figures 3 and 4 the pin positioning member is provided with a rounded end 121 which rides on the periphery of drive wheel 86 to be frictionally driven thereby. A spring 122, overlies spring 112, and is arranged to have one end fastened to lever 117 at 123 to thereby urge the rounded end 121 of the pin positioning member 120 into contact relationship with the periphery of wheel 86. The pin positioning member 120 is provided with a slot 124 which receives the pivoted end of the actuating pin 114. The slot 124 is of sufficient length to permit angular relative movement between levers 110 and 117, as aforementioned, and wide enough to allow the member 120 to swing angularly about its pivot to thereby impart angular movement to actuating pin 114, which has an end 125 slidably carried in an upturned element 126 of the member 120. As best shown in Figures 3 and 4, a spring 127 rotates the member 120 in a counterclockwise direction against the end 128 of the actuating pin which acts as a stop.

Movement of the pickup arm toward the center of a record, as during the playing thereof, under the influence of the stylus 66 tracking inwardly toward the center, rotates the wheel 86 counterclockwise which causes the pin positioning member 120 to swing clockwise, see Figure 3, against the action of spring 127, to thereby move the end 125 of the pin 114, to the left. If the end 125 of the pin 114 is swung far enough to the left, depending on the velocity of the wheel 86, it will be in a position to engage a projection 129 integral with one end of the lever 115. For each revolution of the shaft 26 the cam 113 engages the right end of lever 110 to thereby swing the left end of said lever in a counterclockwise direction so that the rounded end 121 of the member 120 is moved away from the periphery of wheel 86, at which time the spring 127 rotates the member back to its original position against the end 128 of the pin 114. Each time the lever 110 is rotated the actuating pin 114 is also thrust forward a given amount. In this connection it should be noted that lever 110 can swing a given angular distance before lever 117 will be rotated because of the slight amount of travel of pin 118 in the oversized opening 119. This arrangement will permit thrusting the end 125 of the pin 114 forward to engage the projection 129 before the rounded end 121 is actually out of contact with the drive wheel 86. Whether or not the

end 125 of the actuating pin engages the projection 129 of the lever 115 before the pin positioning member 120 is returned by spring 127, depends on how far the end 125 is swung before the pin positioning member is moved out of driving engagement with the wheel 86. The greater the velocity of the wheel 86 the greater the swing of end 125 before the pin positioning member is moved out of contact with the wheel 86. The elements 110, 111, 114, 120, and 127 provide a mechanism which responds to the predetermined velocity of said wheel 86, and is actuatable by said cam 113 to actuate the lever 115. Element 114 is swingable a first predetermined distance in accordance with the velocity imparted to said wheel 86 when the pickup arm is tracking in the playing grooves of the record and swingable a second predetermined distance, which is greater than the first predetermined distance in accordance with the velocity imparted to said wheel when the pickup arm is tracking in the tripping groove of said record.

Lever 115 is normally urged against a stop 130 by a spring 131 having one end fastened to one end of the lever and the other end of the spring is secured to a pin 132 carried on the underside of the platform. The other end of the lever 115 is provided with a downwardly projecting prong 133 which engages an upwardly projecting prong 134, carried by a crank arm 136, pivotally fulcrumed on pin 135 to the top side of the cam 44. A toothed member 137 is pivotally linked to one end of the crank arm for engagement with the interrupted pinion gear 30. A spring 138 biases the crank arm in a direction tending to move the toothed member into engagement with the interrupted gear tooth. The lever 115, crank arm 136, and toothed member 137 provide a latch device actuatable by said pin 114 to initiate cycling. However, actual engagement between the toothed member and the interrupted gear tooth of pinion 28 is normally prevented by the upwardly projecting prong 134 engaging the downwardly projecting prong 133. Any rotation of lever 115, such as would be imparted thereto by the actuating pin 114, will disengage the downwardly projecting prong 133 from the prong 134, to thereby permit crank arm 136 to be rotated under the influence of the spring 138. This action causes the toothed member 137 to move into meshing relationship with the driving pinion gear 28. The cam is now drivably connected to the pinion gear so that rotation of the cam will rotate the teeth 46 thereof into registry with the continuous gear teeth 32 of the driving pinion gear 28.

It is essential that the trip mechanism does not interfere with the tone arm movement during the cycling phase of the phonograph. To insure such non-interference the lever 110 is provided with a cam 141 which slides into a recess 142, located in the periphery of the circular cam element 44, during a non-cycling period. This recess 142 is of sufficient length to allow the end 125 of pin 114 to become disengaged from the projection 129 and to swing to the right, as shown in Figure 3, under the influence of spring 122 before the cam 141 is permitted to ride onto the periphery of the cam 44. When the cam 141 rides onto the periphery of the cam 44 the rounded end 121 of the member 120 will be swung out of contact with the wheel 86.

With reference to Figure 2, a tie rod 144 connects the lever 115 to the push button selector control 145 in a manner such that manually depressing any one of the buttons 146 downwardly

a predetermined distance will rotate lever 115 to disengage prongs 133 and 134 and hence release the lever 136 on which the toothed member 137 is carried. The toothed member is now moved into engagement with the pinion gear. The manual control permits cycling the phonograph, that is, changing records, anytime during the playing period. This push button selector mechanism forms no part of the present invention and will therefore not be described in detail.

In sensing the end of the playing period of a record the trip mechanism functions as follows: As the stylus tracks inwardly toward the center of a record the tone arm swings inwardly, thereby revolving the wheel 86, which in turn rotates the pin positioning member 120. The stylus and hence the pickup arm track inwardly toward the center of a record a predetermined distance during each revolution of the turntable as the record is being played. Since the tripping or non-playing grooves of a record have a greater lead than the playing grooves the wheel 86 will have a greater velocity per revolution of the turntable when the stylus is tracking in the non-playing or tripping grooves than when tracking in the playing grooves.

The cam 113, which rotates at approximately the same speed as the record rides against an end of the lever 110 every revolution causing it to swing about pivot 111. The initial movement of lever 110 under the influence of cam 113 is not enough to move the member 120 out of contact with the wheel 86 so that the pin 114 is thrust forward a predetermined distance depending upon the angle between the member 120 and the lever 110. Continued rotation of cam 113 further swings the lever 110 angularly, which thrusts the pin 114 forward an additional predetermined distance and lifts the rounded end 121, of the pin positioning member, out of contact with the wheel 86. Spring 127 then returns the member 120 to its original position and the action is repeated. When the pickup arm reaches the end of a record, that is, when the stylus passes into a non-playing or tripping groove where the lead is greater than the lead of a playing groove, the pickup arm, and hence the wheel 86 will rotate at a greater velocity to thereby swing the pin 114 at an angle such that the pin will be thrust into the projection 129 of lever 115 before the rounded end 121 of the member 120 is moved out of contact with the wheel 86. This releases the toothed member 137 and thereby initiates a cycle.

Although this invention has been described in connection with certain specific embodiments, the principles are susceptible of numerous other applications that will readily occur to persons skilled in the art.

Having thus described the various features of the invention, what I claim as new and desire to secure by Letters Patent is:

1. In a phonograph apparatus having means for supporting a record during the playing thereof and a pickup arm constituted to cooperate with the grooves in said record, a drive shaft having a pinion gear mounted thereon, cam means connectible to the pickup arm and having teeth arranged thereon for engagement with said pinion gear, a wheel constructed and arranged to be rotated at a predetermined velocity by said pickup arm as it tracks in the grooves of said record, a latch device carried by said cam means for drivably connecting said cam means to said pinion gear and having an element engageable with said

pinion gear, said element normally releasably held out of engagement with said pinion gear, a mechanism drivably connected to said wheel to respond to the predetermined velocity thereof and operatively related to said latch device to actuate the same to release said element for engagement with said pinion gear, said mechanism including a lever pivoted intermediate its ends and pivotally mounting a swingable member on one end thereof, said swingable member having one end arranged in frictional relationship to said wheel and its other end positioned for engagement with said latch device, said swingable member being constituted to rotate a predetermined distance in response to the predetermined velocity of said wheel when the pickup arm is tracking in the tripping groove of said record, and a cam carried by the drive shaft and engageable with the other end of said lever to impart rotation to said lever to thereby thrust said swingable member forward for engagement with the aforementioned latch device.

2. In a phonograph apparatus having a device for supporting a record during the playing thereof and a pickup device constructed and arranged to cooperate with the grooves in said record, a rotatable shaft having a gear mounted thereon, a rotatable cam member having teeth thereon arranged for meshing relationship with said gear, means connecting said record supporting device and said pickup device to said cam member, a latch mechanism for controlling engagement between the gear and cam member and normally disconnecting said gear from said cam member, said latch mechanism operable upon movement of said pickup device into the tripping groove of said record to drivably connect said gear to said cam member, and a velocity sensitive mechanism responsive to movement of said pickup device in the grooves of said record, said velocity sensitive mechanism including a lever pivoted intermediate its ends, with one end lying adjacent said rotatable shaft and the other end lying adjacent said latch mechanism, said other end of the lever being provided with an actuating element operatively related to said pickup device to be driven at one rate of speed when the pickup device is following in the playing groove of the record and at a different rate of speed when the pickup device is following in the tripping groove of a record, and means carried by the rotatable shaft for imparting a periodic rotation to said other end of the lever, said latch mechanism having a portion thereof lying in the path of said actuating element to be driven thereby when the latter is driven at said different rate of speed.

3. In a phonograph apparatus having a pickup arm with a stylus for following in the grooves of a record to be reproduced, power means, means drivably connecting said pickup arm to said power means for positioning said pickup arm with respect to a record and comprising driving and driven gears, a latch mechanism having a part carried by one of the gears for engagement with the other gear, said part being normally releasably held out of engagement with said other gear for disconnecting said pickup arm from said power means when said arm follows in the playing groove of said record, said part being releasable for engagement with said other gear for connecting said pickup arm to said power means when said arm follows in the tripping groove of said record, an actuating lever having one end operatively related to said power means, and means supported on the other end of said lever and

movable into a position for engagement with said latch mechanism under the influence of the pickup arm when the latter follows in the tripping groove of a record for actuating said latch mechanism to thereby cause release of said part.

4. In a phonograph apparatus having a pickup arm with a stylus for following in the grooves of a record to be reproduced, a rotatable shaft provided with a gear, means drivably connecting said pickup arm to said gear for positioning said pickup arm with respect to said record and comprising a cam constructed and arranged to be drivably connected to said gear, a latch mechanism having a part arranged on the cam to disconnect said pickup arm from the gear when said arm follows in the playing groove of said record, said part being moved to a position to connect said pickup arm to said gear when said arm follows in the tripping groove of said record, means operatively related to said pickup arm including a first element rotatable in an arc when said pickup arm follows in the playing groove of said record and rotatable in a greater arc when the arm follows in the tripping groove of the record and a second element arranged to follow the movement of the first element and radially actuatable with respect to the first element, and means for imparting an actuating force to said second element when said first element is rotated in said greater arc to cause actuation of the latch mechanism, said last-named means including a lever pivoted so that one of its ends is operatively related to said shaft to be rotated thereby and its other end is operatively related to said latch mechanism via said second element.

5. In a phonograph apparatus having a pickup arm with a stylus for following in the grooves of a record to be reproduced, power means, means drivably connecting said pickup arm to said power means for positioning said pickup arm with respect to a record and comprising driving and driven gears, a latch mechanism having a part carried by said driven gear for engagement with said driving gear, said part being normally releasably held out of engagement with said driving gear for disconnecting said pickup arm from said power means when said arm follows in the playing groove of said record, said part being releasable for engagement with said driving gear for connecting said pickup arm to said power means when said arm follows in the tripping groove of said record, an actuating lever having one end operatively related to said power means, and means supported on the other end of said lever and movable into a position for engagement with said latch mechanism under the influence of the pickup arm when the latter follows in the tripping groove of a record for actuating said latch mechanism to thereby cause release of said part, said movable means receiving its actuating force from said power means by means of said lever.

6. In a phonograph having a turntable for supporting a record during the reproduction thereof, a pickup arm with a stylus for following in the grooves of said record, power means, means drivably connecting said pickup arm to said power means for positioning said pickup arm with respect to said record and comprising driving and driven gears, a latch mechanism having a part supported on said driven gear for engagement with said driving gear, said part being normally releasably held out of engagement with said driving gear for disconnecting said pickup arm from said power means when said pickup arm follows

in the playing groove of said record, said part being releasable for engagement with said driving gear for connecting said pickup arm to said power means when said pickup arm follows in the tripping groove of said record, an actuating lever having one end operatively related to said power means and its other end operatively related to said latch mechanism, and means mounted on said other end of the lever operatively related to said pickup arm and to said latch mechanism and including an element to be moved to a first predetermined position under the influence of the pickup arm when the latter follows in the tripping groove of said record and moved to a second predetermined position by said lever to cause engagement of said element with said latch mechanism thereby causing said part to be released for engagement with said driving gear.

7. In a phonograph apparatus having a pickup arm with a stylus for following in the grooves of a record to be reproduced, a rotatable shaft provided with a gear, means drivably connecting said pickup arm to said gear for positioning said pickup arm with respect to said record and comprising a cam constructed and arranged to be drivably connected to said gear, a latch mechanism having a part arranged on the cam for driv-

ing engagement with said gear and manually out of engagement therewith when said arm follows in the playing groove of said record, first and second levers pivoted about a common pivot, said second lever having one end operatively related to said power means, a first element rotatable about a center on said first lever, and a second element operatively connected to said latch mechanism and rotatable about a center on the other end of said second lever, said first element drivably connected to said pickup arm and to said second element to rotate the latter about its center, said second element being actuable by said second lever to cause actuation of the latch mechanism.
